J. SCHADE,
LOOSE LEAF BINDER,
APPLICATION FILED MAY 11, 1920.

1,402,018.

Patented Jan. 3, 1922.

UNITED STATES PATENT OFFICE.

JOHN SCHADE, OF HOLYOKE, MASSACHUSETTS, ASSIGNOR TO NATIONAL BLANK BOOK COMPANY, OF HOLYOKE, MASSACHUSETTS.

LOOSE-LEAF BINDER.

1,402,018.

Specification of Letters Patent.

Patented Jan. 3, 1922.

Application filed May 11, 1920. Serial No. 380,509.

To all whom it may concern:

Be it known that I, JOHN SCHADE, a citizen of the United States, residing at Holyoke, Hampden County, State of Massachusetts, have invented certain new and useful Improvements in Loose-Leaf Binders; and I do declare the following to be a full, clear, and exact description of the invention, such as will enable others skilled in the art to 10 which it appertains to make and use the same.

This invention relates to certain new and useful improvements in a loose leaf binder and it aims to simplify the construction so 15 that persons neither mechanically inclined nor skilled will have no difficulty in operating and manipulating the same.

A further object resides in the novel interlocking joint between the ends of the 20 binder ring which consists in laterally notched terminal portions that automatically engage when the sides of the ring are compressed owing to the inherent lateral twisting of the wire.

25 In the binder herein disclosed, three binder rings are employed but obviously a larger or smaller number may be supplied to meet the specific demands. Furthermore, modifications in design and structure can be 30 resorted to without departing from the spirit of the invention as exemplified in the drawing wherein.

Figure 1 is an open plan view of the improved loose leaf binder:

35 Figure 2 is a transverse section thereof on line 2—2 of Figure 1:

Figure 3 is a fragmental plan view of the ring supporting plate:

40 Figure 4 is a detailed elevation of the ring partly opened; and Figure 5 is a transverse section through Figure 2 on line 5—5.

In the drawing the numeral 1 designates the cover of the binder, 2 the back thereof reinforced by the metal back plate 3, and 45 4 the ring support which is provided lengthwise with a central, hollow or inverted V-shaped rib 5 and paralleling inturned or rolled side edges 6. At intervals along the inwardly rolled side edges are provided 50 opposing pairs of recesses or ring seats 7 and intermediate the seats are cut-outs or transverse slots 8 in the rib 5.

The binder rings 9 are inserted in the slots 8 and engaged in the respective pairs 55 of seats 7 where they are securely retained

by means of a locking pin 10 common to all the rings. This pin is substantially the length of the rib and passes over the lower arcs of the rings which latter normally hold the pin up in the apex of the rib and aid 60 in guiding the point over the succeeding ring. Each ring consists of a section of a helix indicated by the dotted showing of Fig. 4, having its terminal portions formed with lateral notches 11 that open in opposite directions away from one another, when the ring is fully opened. To interlock the terminals the latter are sprung past one another in an axial direction when the inherent resiliency of the metal will tend to 65 contract the ring so that its extremities will laterally engage as indicated in Figure 4, and the notches 11 will then be within contiguous portions of the ring terminals. The terminals in this position are, therefore, under laterally directed or twisting tension 70 whereby upon compressing the sides of the ring the notched ends will spring into interlocking relation which can only be separated by laterally spreading them apart. 80

The ring support 4 is secured to the back plate 3 by striking up pairs of opposing cleats 12 through the slots 8 and bending them outwardly back onto the ring supporting plate. This novel manner of anchoring 85 the support obviates the necessity of additional securing means and permits the lateral portions or ring seats to yield for disposing the lower arcs of the rings sufficiently 90 low in the slots 8 to readily pass the locking pin thereover. The resilient mounting of the rings affords a frictional contact between the latter and the locking pin for preventing accidental dislodgment of said pin. 95

This construction provides a firmer and more durable binder which is so simple in make-up as to be most easily operated by any unskilled clerk. The back plate and ring support can obviously be an integral structure, or the back plate entirely eliminated. The rings automatically interlock 100 merely by compressing the sides of the rings.

From the foregoing it will be noted that a binder is provided in which the binder rings are quickly attachable to and detachable from the cover so that the user of the book can disengage the rings from the cover and file away the entire filler mounted on the rings. Since the rings are produced and obtained at a very small cost the cover can 105 110

readily be equipped with a new set of rings for refilling. The construction is therefore economical, can be manufactured at a very low cost, and will lend itself to any desired 5 spacing of rings as one may wish, requiring more or less spacing of slots 8 and seats 7. To open the binder ring it is merely necessary to pull the interlocked ends apart to one side and then permit them to spring apart 10 endwise due to their inherent resiliency.

By making the rings and ring supports 15 separate, the shipment of the goods is greatly facilitated because the covers can be spread out and packed together flat, and the rings can be sent separately, thus greatly decreasing the bulk and expense in shipping.

The same cover and ring support may be used for different sizes of rings. The user 20 may use a small size ring and if he discovers that he rapidly fills the rings he can remove them and file them away with the loose leaves contained on the rings and then substitute larger rings, or, in a three or four ring binder, he can have the two end rings of 25 a larger size, as for instance, for holding certain loose leaves, and have the intermediate rings of a smaller size for holding memorandum or other slips, the two sets entirely separate.

30 What is claimed is:

1. A loose leaf binder comprising a back plate, a ring supporting plate having its side edges rolled inwardly to provide resili-

ent ring engaging portions which are formed with seats to receive the binder 35 rings, said plates secured together, and movable means between the resilient portions for securing a ring to its seats.

2. A loose leaf binder comprising a back plate, a ring supporting plate having its 40 side edges rolled inwardly to provide resilient ring engaging portions which are formed with seats to receive the binder rings, said ring supporting plate having an intermediate rib formed transversely with slots to receive the lower arcs of the rings when the latter are engaged in their seats, said back plate having clinching lips struck therefrom up through the slots of the ring supporting plate to secure the two plates together, and 45 means for holding the rings in the slots.

3. In a loose leaf binder, a ring supporting plate having a central, longitudinal rib and inwardly rolled, ring supporting side edges, said rib formed with a transverse 55 slot, and a locking pin movable within the rib across the slot for securing a ring therein and on the side edges.

4. In a loose leaf binder, a ring supporting plate having spaced and yieldable ring 60 engaging parts, and a movable ring lock between the parts frictionally secured in its operative position by the cooperation of the latter.

In testimony whereof I affix my signature. 65
JOHN SCHADE.
